UNITED STATES PATENT OFFICE.

CHARLES H. LAY, OF BROOKLYN, NEW YORK, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,203,123.

Specification of Letters Patent.

Patented Oct. 31, 1916.

Application filed August 27, 1913. Serial No. 786,886.

To all whom it may concern:

Be it known that I, CHARLES H. LAY, a citizen of the United States, residing at Brooklyn, in the county of Kings and State 5 of New York, have invented certain new and useful Improvements in Railway Signaling, of which the following is a specification.

My invention relates to railway signaling for stretches of single track over which 10 traffic moves in both directions, such for example as for stretches of single track between passing sidings.

I will describe one form of railway signaling system embodying my invention and 15 will then point out the novel features thereof in claims.

In the accompanying drawings, Figure 1 is a diagrammatic view showing a stretch 20 of railway track having applied thereto one form of railway signaling system embodying my invention. Figs. 2 and 3 are views similar to Fig. 1, but showing the operation of the signaling apparatus during the passage of a car or train through a portion of the 25 stretch.

Similar reference characters refer to similar parts in each of the several views.

Referring to the drawings, A designates a stretch of railway track over which traffic 30 moves in both directions between two passing sidings C and D. Traffic through the stretch A from west to east is governed by signals 1, 3 and 5 located at intervals, and traffic through the stretch from east to west 35 is governed by signals 2, 4 and 6 located at intervals. With this arrangement of signals, it is desirable that when a car or train enters the stretch A from either end, it should cause all of the signals governing traffic in 40 the direction opposite to the direction of movement of the car or train to indicate stop. It is desirable, however, that succeeding cars or trains moving in the same direction should be permitted to enter and 45 pass through the stretch, but that cars or trains thus moving in the same direction should be separated by at least the distance between two successive signals; that is, it is desirable that as the car or train proceeds 50 through the stretch A, each signal behind the car or train governing traffic in the direction of movement of the car or train should change to proceed indication as soon as the car or train leaves the territory which is 55 protected by such signal. This operation of

the signals is effected by means which I will now describe.

The stretch A is divided by insulated joints into a plurality of sections $a-a'$, $a'-a^2$, and a^2-a^3 , which sections are provided with track circuits including track relays. In the arrangement here shown, a pair of opposing signals is located adjacent each junction of adjacent sections, but I do not wish to limit myself to this particular location of the signals. As here shown, each section is divided by insulated joints into two sub-sections, each of which is provided with a track circuit comprising the rails of the sub-section, a track battery b and a track 60 relay T' , T^2 , or T^3 , etc. For example, section $a-a'$ is divided into two sub-sections $a-a^4$, and a^4-a' . It is understood, however, that I do not limit myself to this particular arrangement of track circuits for the 65 stretch.

For each signal I provide a signal relay for the control thereof. For example, signal relay R' controls signal 1, signal relay R^2 controls signal 2, etc. Each signal is provided with a controlling circuit which is controlled by the corresponding signal relay; for example, the circuit for signal 2 is from battery B through wire 7, contact 8 of signal relay R^2 , wire 9, signal 2, wire 10 to battery B. The controlling circuit for each of the other signals is similar to that just traced.

Corresponding to each signal, except the end signals 1 and 2, is an auxiliary relay X^6 , 90 etc. For example, auxiliary relay X^6 corresponds to signal 6, auxiliary relay X^3 corresponds to signal 3, etc. These auxiliary relays are controlled by the signal relays as hereinafter explained. Each signal relay, 95 except as hereinafter noted, is provided with a controlling circuit which is controlled by the auxiliary relay corresponding to the signal next in advance governing traffic in the same direction and by the track relays 100 for the section through which the signal corresponding to the signal relay governs traffic. For example, the circuit for signal relay R^2 is from battery B' through wire 16, front contact 11 of auxiliary relay X^4 , wire 105 12, contact 13 of track relay T^3 , wire 17, contact 14 of track relay T^3 , wire 15, signal relay R^2 , wire 10 and common wire O to battery B'. The circuit for each signal relay is similar to that just traced, except that 110

the circuits for signal relays R^5 and R^6 are controlled only by the track relays for sections $a-a'$ and a^2-a^3 , respectively, there being no auxiliary relays corresponding to 5 signals 1 and 2.

Each auxiliary relay is provided with a "pick-up" circuit and a "holding" circuit, which circuits are controlled by the signal relays. The pick-up circuit for each auxiliary relay is controlled by a front contact of 10 the corresponding signal relay and by a front contact of the signal relay for the adjacent signal governing traffic in the opposite direction; for example, the pick-up circuit for auxiliary relay X^4 is from battery B' through wires 16 and 18, front contact 19 of signal relay R^4 , wire 20, front contact 21 of signal relay R^5 , wire 22, auxiliary relay X^4 , wire 23 to battery B' . It will be 15 seen that this pick-up circuit is closed only when relays R^4 and R^5 are both closed. The holding circuit for each auxiliary relay is controlled by a front contact of the corresponding signal relay and by a front contact 20 of the auxiliary relay itself; for example, the holding circuit for auxiliary relay X^4 is from battery B' through wires 16 and 18, front contact 19 of signal relay R^4 , wires 24 and 25, front contact 26 of relay 25 X^4 , wire 27, winding of relay X^4 , wire 23 to battery B' . It will be seen that this holding circuit is closed only when relays R^4 and X^4 are closed. The holding circuit for each auxiliary relay is provided with a branch 30 around the contact of the corresponding signal relay, which branch is controlled by a back contact of the auxiliary relay for the adjacent signal governing traffic in the opposite direction; for example, the branch 35 for the circuit of auxiliary relay X^4 is around contact 19 of relay R^4 , and is as follows: from wire 16, through wire 28, back contact 29 of auxiliary relay X^5 , wire 30 to wire 24. The pick-up and holding circuits 40 for each of the auxiliary relays are similar to those just traced for relay X^4 .

The operation of the apparatus is as follows: When the stretch A is unoccupied by cars or trains, all of the track relays are 45 closed and all of the auxiliary relays are closed, so that all of the signal relays are closed and all signals, therefore, indicate "proceed." Assuming now that a westbound car or train enters the stretch from 50 siding D, the effect on the apparatus is as shown in Fig. 2. Referring now to this view, it will be seen that as the car or train W enters sub-section $a-a'$, it opens track relay T^6 , thereby opening at contact 14 the 55 circuit for signal relay R^2 . The opening of this signal relay opens the circuit for signal 2, which therefore changes to "stop" indication. The opening of track relay T^6 also opens at contact 31 the circuit for signal 60 relay R^5 , which relay then opens and

thereby causes signal 5 to change to stop indication. The opening of signal relay R^5 opens at contact 32 the holding circuit for auxiliary relay X^5 which relay therefore opens, because the branch of its holding circuit is open at back contact 33 of relay X^4 . The opening of auxiliary relay X^5 opens at 70 contact 34 the circuit for signal relay R^3 , which latter causes signal 3 to change to stop indication. Signal relay R^3 similarly 75 causes auxiliary relay X^3 to open, which latter opens the circuit of signal relay R' , thereby causing signal 1 to change to stop indication. It will be seen, therefore, that all of the signals governing traffic in the 80 direction opposite to the direction of movement of the car or train W are caused to change to stop indication. As the car or train W proceeds into sub-section a^4-a' , it opens track relay T^5 and permits track relay 85 T^6 to close, but this has no effect on the circuits for the reason that the circuits controlled by track relay T^5 are the same as those controlled by track relay T^6 .

Referring now to Fig. 3, as the front end 90 of the car or train W enters sub-section $a'-a^5$, it opens track relay T^4 , and when the rear of the car or train leaves sub-section a^4-a' it permits track relay T^5 to close. The opening of track relay T^4 opens 95 at contact 35 the circuit for signal relay R^4 , which relay then opens, thereby causing signal 4 to change to stop indication. The opening of relay R^4 also opens the normal holding circuit for auxiliary relay X^4 , but 100 this latter relay remains closed, because back contact 29 of auxiliary relay X^5 is closed. Auxiliary relay X^5 remains open because its pick-up circuit is open at contact 36 of signal relay R^4 . The closing of 105 track relay T^5 closes the control circuit for signal relay R^2 , which relay therefore closes and causes signal 2 to change to proceed indication. It will thus be seen that as soon as the rear of car or train W has left the 110 section $a-a'$, signal 2 changes to proceed indication, thereby permitting a following westbound car or train to enter the stretch A from the siding D. The closing of track relay T^5 also closes the circuit for signal 115 relay R^6 , which relay closes, thereby causing signal 5 to change to proceed. As the car or train W proceeds into sub-section a^5-a^2 , it opens track relay T^3 and permits track relay T^4 to close, but this has no effect 120 on the circuits. When the entire car or train W has passed into section a^2-a^3 , the closing of track relay T^3 permits signal relay R^4 to close, thereby closing at contact 36 the pick-up circuit for auxiliary relay 125 X^5 , so that this latter relay then closes. The closing of signal relay R^4 also causes signal 4 to change to proceed indication, for the same reasons as hereinbefore explained for signal 2, so that a following westbound car 130

or train may then enter section a' — a^2 . After the car or train W has left the stretch A, signals 6 and 1 change to proceed indication for reasons similar to those hereinbefore explained for the other signals and the circuits and apparatus are then again in the conditions in which they are shown in Fig. 1.

The operation of the apparatus for the passage of an eastbound car or train through the stretch A is similar to that just explained and need not be traced herein.

Although I have herein shown and described only one form of railway signaling system embodying my invention, it is understood that various changes and modifications may be made therein within the scope of the appended claims without departing from the spirit and scope of my invention.

Having thus described my invention, what I claim is:

1. In combination, a stretch of railway track, signals located at intervals for governing traffic in one direction through the stretch and other signals located at intervals for governing traffic in the other direction through the stretch; a signal relay for each signal for the control thereof; an auxiliary relay corresponding to each signal; a circuit for each signal relay controlled by the auxiliary relay corresponding to a signal in advance governing traffic in the same direction; track circuits for the stretch including track relays for controlling said signal relay circuits; a pick-up circuit for each auxiliary relay controlled by the signal relay for the corresponding signal and by the signal relay for a signal governing traffic in the other direction, and a holding circuit for each auxiliary relay controlled by the signal relay for the corresponding signal and by the auxiliary relay for the said signal governing traffic in the other direction.

2. In combination, a stretch of railway track, signals located at intervals for governing traffic in one direction through the stretch and other signals located at intervals for governing traffic in the other direction through the stretch; a signal relay for each signal for the control thereof; an auxiliary relay corresponding to each signal; a circuit for each signal relay controlled by the auxiliary relay corresponding to a signal in advance governing traffic in the same direction; track circuits for the stretch including track relays for controlling said signal relay circuits; a pick-up circuit for each auxiliary relay including a front contact of the signal relay for the corresponding signal and a front contact of the signal relay for an adjacent signal governing traffic in the opposite direction, a holding circuit for each auxiliary relay including the said front contact of the signal relay for

the corresponding signal and a front contact of the auxiliary relay, and a branch for said holding circuit around the front contact of the signal relay for the corresponding signal and including a back contact of the auxiliary relay for said adjacent signal governing traffic in the opposite direction. 70

3. In combination, a stretch of railway track divided into a plurality of sections, a pair of opposing signals located at substantially the junction of each two adjacent sections for governing traffic through said two adjacent sections respectively, a signal relay for each signal for the control thereof, an auxiliary relay corresponding to each signal, a circuit for each signal relay controlled by the auxiliary relay corresponding to the signal next in advance governing traffic in the same direction, a track circuit for each section including a track relay for controlling the signal relay for each signal governing traffic through the section, a pick-up circuit for each auxiliary relay controlled by the signal relay for the corresponding signal and by the signal relay for the adjacent signal governing traffic in the other direction. 80

4. In combination, a stretch of railway track divided into a plurality of sections, a pair of opposing signals located at substantially the junction of each two adjacent sections for governing traffic through said two adjacent sections respectively, a signal relay for each signal for the control thereof, an auxiliary relay corresponding to each signal, a circuit for each signal relay controlled by the auxiliary relay corresponding to the signal next in advance governing traffic in the same direction, a track circuit for each section including a track relay for controlling the signal relay for each signal governing traffic through the section, a pick-up circuit for each auxiliary relay controlled by a front contact of the signal relay for the corresponding signal and by a front contact of the other adjacent signal relay, a holding circuit for each auxiliary relay controlled by said front contact of the signal relay for the corresponding signal and by a front contact of the auxiliary relay, and a branch for each holding circuit around the said front contact of the corresponding signal relay and including a back contact of the adjacent auxiliary relay. 100

5. In combination, a stretch of railway track, signals located at intervals for governing traffic in one direction through said stretch, a signal relay for each signal, an auxiliary relay corresponding to each signal, a circuit for each signal relay controlled by the auxiliary relay for the signal next in 110

120

125

130

133

advance, track circuits for the stretch including track relays for controlling said signal relay circuits, and means for said auxiliary relays controlled by the signal relays for holding said auxiliary relays energized when a car or train passes through the stretch in the direction in which said signals govern traffic, and for deenergizing the auxiliary relays in advance of a car or

train passing in the other direction through 10 the stretch.

In testimony whereof I affix my signature in presence of two witnesses.

CHARLES H. LAY.
